(57) **CLAIM**

The ornamental design for a microphone stand, as shown and described.

DESCRIPTION

FIG. 1 is a perspective view of the microphone stand, showing our new design;

FIG. 2 is a perspective view thereof from another angle;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the microphone stand, illustrated with example attachment mechanisms.

The broken lines immediately adjacent the shaded areas represent the bounds of the claimed design while all other broken lines depict portions of the microphone stand that form no part of the claimed design.
